US00D801950S

(12) **United States Design Patent** (10) **Patent No.:** **US D801,950 S**
(45) **Date of Patent:** **** Nov. 7, 2017**

(54) **COMMUNICATION DEVICE**

(71) Applicant: **Sony Mobile Communications Inc.**,
Tokyo (JP)

(72) Inventors: **Yusuke Otani**, Tokyo (JP); **Keita Hibi**,
Tokyo (JP); **Daisuke Ishii**, Tokyo (JP);
Kazuhiko Ishida, Tokyo (JP); **Simon Henning**, Lund (SE); **So Morimoto**,
Surrey (GB); **Hiroya Fujii**, Surrey (GB);
Pietro Russomanno, Surrey (GB); **Jake Rich**, Surrey (GB); **Yuki Kubota**, Tokyo (JP)

(73) Assignee: **SONY MOBILE COMMUNICATIONS INC.**, Tokyo (JP)

(**) Term: **15 Years**

(21) Appl. No.: **29/555,302**

(22) Filed: **Feb. 19, 2016**

(51) LOC (10) Cl. **14-01**
(52) U.S. Cl. **D14/223**

(57) **CLAIM**

The ornamental design for a communication device, as shown and described.

DESCRIPTION

FIG. 1 is a front, top, right perspective view of a first embodiment of a communication device showing our new design;

FIG. 2 is a front, bottom, right perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and

FIG. 8 is a bottom plan view thereof.

FIG. 9 is a front, top, right perspective view of a second embodiment of a communication device showing our new design;

FIG. 10 is a front, bottom, right perspective view thereof;

FIG. 11 is a front elevational view thereof;

FIG. 12 is a rear elevational view thereof;

FIG. 13 is a left side elevational view thereof;

FIG. 14 is a right side elevational view thereof;

FIG. 15 is a top plan view thereof; and,

FIG. 16 is a bottom plan view thereof.

The broken lines depict environment that forms no part of the claimed design.

1 Claim, 8 Drawing Sheets
